UNITED STATES PATENT OFFICE.

LULA CRUMBLY, OF FORT WORTH, TEXAS.

BRACING-GARMENT.

No. 839,555.

Specification of Letters Patent.

Patented Dec. 25, 1906.

Application filed April 21, 1905. Serial No. 256,791.

To all whom it may concern:

Be it known that I, LULA CRUMBLY, a citizen of the United States, residing at Fort Worth, Texas, have invented certain new and useful Improvements in Bracing-Garments, of which the following is a specification.

My invention relates to garments, and more particularly to a garment which some-
what resembles a corset, but having the func-
tions of a body-brace; and the object is to
produce a garment which will permit easy
movement and carrying of the body and yet
preserve the form of the body.

This garment is intended for the many
thousands of women who are suffering from
female weakness, particularly for women who
are employed in factories and stores where
they have to stand on their feet from morn-
ing till night, for those who have to labor at
the wash-tub and ironing-table, for those
who have to attend to household duties, and
for those engaged in many other occupations
who are afflicted with excruciating pains,
heaviness in the loins, and despondent tired-
out feeling, caused by pressure of the abdomi-
nal parts on the pelvis and the womb. I
have provided a kind of a substitute for a
corset, but which has none of the bad effects
of the corset.

This garment will serve as a support for
the bust, and will maintain the form of the
bust without pressing on the abdomen, and
will support or brace the lower part of the
abdomen, and thus relieve the pressure of the
abdomen on the womb and on the pelvis.
Other objects and advantages will be fully
understood from the following description,
and the invention will be more particularly
pointed out in the claim.

Reference is had to the accompanying
drawings, which form a part of this applica-
tion and specification:

Figure 1 is a perspective view of the gar-
ment as applied to a woman. Fig. 2 is an
interior view of the garment in detail. Fig.
3 is a broken view of the garment, showing
the manner of fastening the abdominal
braces.

Similar characters of reference are used to
indicate the same parts throughout the sev-
eral views.

This garment is provided with stays only

in the back part. The parallel dotted lines
in the back indicate stitches which sew the 55
parts of the cloth together between the stays.
The back of the garment is gored at *a* to pro-
vide for expansion of persons having large
hips. The bust portions *b* have no stays, such
as corset have, but these portions are pro- 60
vided with some stiffening material, and
made to conform to the contour of the bust,
these parts being concave in Fig. 2. The
bust portions terminate just below the pit of
the stomach, substantially at the waist-line. 65
The abdominal portions *c* are attached to the
bust portions *b* and to the back portions *d*.
The garment is preferably open in front and
provided with hooks *g* and eyes *h* for fasten-
ing devices. The parts *c* are also made to 70
conform to the rotundity of the body, being
concave, as shown in Fig. 2. The abdominal
braces *i* and *j* are attached to the lower part
of the garment and extend substantially
from the back portion *d* and lap at the front, 75
as shown in Fig. 3. These braces may have
hooks *g* to engage eyes *h* on the brace *j*. The
braces are adjustably fastened together by
straps *k*, which carry buckles *m*, which en-
gage the straps *n* on the brace *j*. The ab- 80
dominal portions *c* may be made of suitable
cloth and must be without stays or stiffen-
ing material. The usual shoulder-straps *e*
are provided.

The garment above described has no 85
stays to press down the abdomen and noth-
ing about the waist to prevent freedom of
movement of the body; but the bust por-
tions are adapted to preserve the form, and
the back portion will brace the body, and the 90
shoulder-straps will hold the garment up, so
that the pressure of the abdomen on the
womb and pelvis is relieved. It is thus seen
that a garment is provided which is adapted
for women who work and also for women 95
who are *enceinte*. This garment will take
the place of a corset and preserve the form
of the bust and other portions of the body,
and yet permit freedom of movement of the
body, so that a person can work without be- 100
ing tired-out by such a garment as a corset.

Having fully described my invention, what
I claim as new, and desire to secure by Let-
ters Patent, is—

A garment having a back portion provided 105
with stays extending to the bottom of the

garment, bust portions provided with stiffening material terminating at the waist-line, and abdomen portions connected to the bust portions and enveloping the abdomen and connected to the sides of said back portion, the abdomen portions being of pliable material and adapted to support the abdomen.

In testimony whereof I set my hand, in the presence of two witnesses, this 3d day of April, 1905.

LULA CRUMBLY.
